UNITED STATES PATENT OFFICE

JACOB L. BLALACK, OF LOS ANGELES, CALIFORNIA

EARTHQUAKE-OPERATED SAFETY AUTOMATIC CIRCUIT BREAKER

Application filed March 28, 1927. Serial No. 178,897.

This invention relates to circuit breakers.

The general object of this invention is to provide an improved circuit breaker which will be actuated to break an electric circuit by earthquake tremors.

Another object of the invention is to provide an improved circuit breaker wherein means is provided for breaking the electric circuit either by earthquake tremors or by excessive heat.

A further object of my invention is to provide a novel circuit breaker which will be actuated by excessive heat from an accidental fire.

Other objects and advantages of this invention will be apparent from the following description taken in connection with the accompanying drawings wherein:

Fig. 1 is a side elevation of my improved circuit breaker showing it attached to a wall or support.

Fig. 2 is a front face view of the device.

Fig. 3 is a front face view of the device with the cover removed showing the various contact elements.

Fig. 4 is a section taken approximately on line 4—4 of Fig. 2.

Fig. 5 is a section taken on line 5—5 of Fig. 3, and

Fig. 6 is a view similar to Fig. 3 showing the device actuated to break the electric circuit by excessive heat.

Referring to the drawings by reference characters I have indicated my improved circuit breaker generally at 10. The device 10 may be attached to any suitable support such as a rafter, column, beam, or wall 11 as shown in Fig. 1.

The device 10 as shown in the drawing comprises a base 12 having integral therewith and projecting therefrom a cylindrical housing 13. The base 12 and the housing 13 are preferably made of an insulated material such as porcelain or any other suitable substance. Within the housing 13 are mounted a stationary metallic arm 14 and a pivoted metallic arm 15. The stationary arm 14 is shown as supported in the housing 13 by securing it thereto by a bolt 16 and a nut 17. The bolt 16 and nut 17 also serve as a terminal

to which may be secured by a nut 18 an electric wire 19.

For supporting the arm 15 I provide a metal bracket 20 having a pair of spaced ears 21 thereon between which is mounted for pivotal movement by a screw 22, the arm 15. The bracket 20 is shown as secured to the housing 13 by a bolt 23 and a nut 24. The bolt 23 and nut 24 also serve as a terminal to which may be secured by a nut 25 an electric wire 26.

For retaining the arm 15 in a horizontal position I provide thereon an upstanding lip 27 which engages a rod 28. The rod 28 is preferably made of a material fusible at a low heat and is supported in a bracket 29 which is secured to the housing by a screw 30. As shown in the drawing the screw 30 engages a nut 31 which is cemented in a recess 32 of a boss 33, the cement covering the nut and the end of the screw so that there is no electric conductive portion of the bracket 29 exposed externally of the housing 13, whereby a short circuit might be accidentally made and fuse the rod 28.

The free ends of the arms 14 and 15 are bent at 34 and 35 to form two halves of a circular seat for supporting a metallic conducting sphere 36. The bends of the portions 34 and 35 are preferably all on a radius thus eliminating the arcing of the electrical current from one arm to the other when the ball 36 has fallen, when the device is used on a circuit for which it was intended.

The housing 13 is shown as provided with a cover 37 which may be detachably secured to the housing as by screw threads 38 or in any other suitable manner. The cover 37 is preferably provided with a plurality of apertures 39 whereby in case of a fire in the vicinity of the device, the excessive heat will fuse the pin or rod 28 letting the arm 15 drop.

As shown in Figs. 1 and 2 of the drawing, my device 10 is interposed in the positive wire of a two wire system, but one of my devices 10 may also be interposed in the negative wire if so desired, and also one of my devices may be interposed in each wire of a three wire system if desired.

The device 10 is preferably interposed in the main feed wires of a building either just

before entering the building or just after entering. Normally the electric circuit will pass from the wire 26 through the bracket 20 and arm 15 to the sphere 36, from whence it 5 passes through the arm 14 into the wire 19, thus forming a closed circuit from the wire 26 to the wire 19.

The heavy tremors of a serious earthquake will rock the sphere 36, unseating it from the 10 portions 34 and 35 whereupon the arms 14 and 15 will be unbridged and thereby cause an open circuit between the wires 19 and 26 through which no electric current will flow, thus eliminating the danger of the electrical 15 system in the building becoming shorted and causing a fire.

When the rod 28 is fused as previously stated, by fire in the vicinity of the device, the weight of the arm 15 and the sphere 36 20 will cause the arm 15 to swing about the pivot screw 22 and assume a substantially vertical position as shown in Fig. 6, thus causing an open circuit between the wires 19 and 26 through which no electric current will flow.

From the foregoing description it will be apparent that I have provided a novel form 25 of electric circuit breaker which will be caused to actuate to form an open circuit by either heavy earthquake tremors or by excessive heat and one which is simple in construction and positive in operation.

What I claim is:

1. In a circuit breaker, a pair of spaced electrical conductive elements, a movable conductive element connecting said spaced elements and forming a closed circuit between said spaced elements, a seat for said movable element, said movable element being readily displaced by earthquake tremors to cause an open circuit between said pair of elements.

2. In combination with a pair of spaced electrical conductive elements, a third electrical conductive element, said third element 45 adapted to normally form a closed circuit between said spaced elements and means to mount said third element for movement out of engagement with said spaced elements by earthquake tremors to cause an open circuit to be formed between said spaced elements.

3. A circuit breaker comprising a housing, a pair of spaced conductor arms in said housing, movable means for forming a contact between said spaced arms, one of said arms being pivotally mounted, means to retain said pivoted arm in an operative position, said means being fusible and adapted upon fusion to release said arm for movement whereupon 50 said contact means will move out of engagement with said arms, said contact means being mounted for movement out of engagement with said spaced arms by earthquake tremors.

4. In a circuit breaker a housing, a cover

for said housing, said cover being perforated, a pair of spaced arms in said housing, means to make electrical contact with said arms, each of said arms having their adjacent arms bent to form a portion of a seat, a sphere 70 adapted to be positioned in said seat to form contact between said spaced arms, one of said spaced arms being pivotally mounted, a lip on said arm, a rod engaging said lip to normally hold said arm in an operative position, said rod being fusible at a low temperature, 75 said sphere being adapted to be moved out of engagement with said pair of spaced arms by earthquake tremors, thus causing breaking contact between said arms, and said fusible rod being adapted to be fused by a low degree of heat thereby releasing said lip whereupon said pivoted arm will move and cause said sphere to move and break contact 80 between said spaced arms.

In testimony whereof, I hereunto affix my signature.

JACOB L. BLALACK.
